UNITED STATES PATENT OFFICE.

WILLIAM E. AYCOCK, OF MOULTRIE, GEORGIA, ASSIGNOR TO AYCOCK WOOD-BRICK VENEER CO., OF MOULTRIE, GEORGIA, A CORPORATION OF FLORIDA.

WEATHERBOARDING.

Application filed May 31, 1922. Serial No. 564,797.

To all whom it may concern:

Be it known that I, WILLIAM E. AYCOCK, a citizen of the United States, and a resident of Moultrie, Georgia, have invented new and useful Improvements in Weatherboarding, which are fully set forth in the following specification.

This invention relates to an improved weatherboarding or siding for use in buildings, and has for its object the provision of weather-boarding or siding which may be readily applied to produce a weather-tight joint and present a finished and attractive appearance.

15 A further object is to provide a weather-boarding or siding which, when applied on the building and properly painted, shall present the appearance of a brick wall, preferably with "rake" joints.

20 The present invention is an improvement on Patent No. 1,171,081, granted to me February 8, 1916, in which the weather-board is of uniform cross-section from edge to edge, and one of the objects of the present invention is to secure all of the benefits and advantages set forth in my said patent while economizing in the amount of lumber employed in producing the siding, to the end that the first cost of the siding may be reduced and the freight also materially reduced owing to the decreased bulk and weight of the siding.

25 By means of the present invention I am enabled to form two weather boards or strips of siding from approximately the same amount of lumber that was required to form one weather-board or strip of siding of the construction shown and described in my said patent, while retaining all the advantages 30 of said construction. In the manufacture 40 of the siding of my present invention, I take a strip of lumber, preferably one inch in thickness and four inches in width, and with a suitable band-saw I divide this strip longitudinally into two strips of uniform dimensions, each of said strips being approximately one-third of an inch thick on its thinner edge and two-thirds of an inch on its thicker edge. These strips of weather-boarding 45 are designed to be applied to the wall with the thin edge downward and the thick edge upward. In the upper edge of the strip of siding and on the outer face thereof are formed two longitudinally extending rabbets, one above the other. Each of the rabbets has a base or bottom portion which, when the siding is applied in position on the wall, is approximately horizontal both in longitudinal and transverse directions. The face of the lower rabbet is parallel with the outer face of the weather-board, and, when the latter is applied in position on the wall, is substantially vertical. The face of the upper rabbet is inclined inward or away from the front face of the weather-board. 60 Preferably, the vertical measurement of the lower rabbet is approximately that of the vertical measurement of a "rake" joint in a brick wall, while its horizontal depth is approximately the depth of the ordinary rake joint. The vertical measurement of the upper or inwardly inclined rabbet may be of any desired extent, preferably, however, being sufficient to afford ample room for lap of the next superposed strip of siding and 70 for nailing. The base of the upper rabbet in its transverse measurement is such that, when added to the depth or transverse measurement of the lower rabbet, it will exactly equal the thickness of 75 the lower edge of the strip of siding. Vertically extending grooves, corresponding in width and depth with the dimensions of the lower rabbet, are formed in the face of the strip of weather-board to simulate the vertical "rake" joints in brickwork.

One form of the invention is shown in the accompanying drawings, in which:—

Fig. 1 is a perspective view showing strips of weather-boarding in place in a wall;

Fig. 2 is a sectional perspective view through part of a wall showing my improved siding in position;

Fig. 3 is an end elevation of a board, showing how the same is divided to form 95 two weather-boards; and

Fig. 4 is a similar view of one of the weather-boards, the material cut away to form the same being indicated in dot and dash lines.

Referring to the drawings, wherein like reference numerals indicate like parts throughout the several views, 1 indicates a board divided longitudinally by any suitable saw, such as a band-saw, into two pieces 105 2 and 3 of uniform dimensions from which are formed the strips of weather-boarding 4. The kerf made by the saw extends diagonally through the board in such manner that each piece or strip shall have an approxi- 110

mate thickness of one-third of an inch at one edge and two-thirds of an inch at the opposite edge.

The side of the strip along the diagonal 5 cut forms the rear face of the board and the opposite side the front face. Each weather-board or strip of siding is provided on the front face of its thicker edge portion with two longitudinally extending rabbets 5 and 6, one above the other. The lower rabbet 5 is provided with a horizontal bottom 7 and a vertical face 8. The upper rabbet is provided with a horizontal bottom 9 and a rear- 10 wardly inclined face 10. The inclined rear 15 face 11 of each weather-board terminates at the thicker edge of the board in a surface 12 parallel with the front face of the board.

In applying the weather-boards to the wall, they may be applied in any usual way, 20 either directly to the studding or, preferably and as here shown in Fig. 2, the weather-board is secured to the sheathing 13 and when in position, whether as applied to the sheathing or directly to the studding, the 25 weather-boarding is applied with the rabbeted thicker portion uppermost and the beveled portion 12 (which is parallel with the front face 4 of the board) resting against the sheathing or against the interposed 30 building-paper 17 and the lower thinner edge of each board resting on the bottom 9 of the rabbet 6 of the board immediately below and nailed through such thin edge and the upper edge of the lower board. The 35 thinner lower edge of the first board is received in a rabbet 14 of a water table 15 suitably secured to the sheathing at the desired height from the ground. Since the combined depths of the rabbets 5 and 6 are 40 equal to the thickness of the weather-board at its lower edge, it follows that the overhang at the lower edge of each board is exactly equal to the distance from the front face of the weather-board to the face 8 of the rabbet 5, so that there is formed a longitudinal 45 groove of uniform depth at top and bottom and of a height equal to the height of the face 8 of the rabbet 5.

Each of the boards is provided with 50 equally spaced vertical grooves, the spacing being preferably approximately equal to the length of a brick, said vertical grooves being of the same dimensions as the longitudinal grooves formed by the rabbet 5 and the overhang of the board immediately above. The 55 result is that, when the weather-boards are in place, the wall has the appearance shown in Fig. 1, that is the appearance of a brick wall with "rake" joints; and when the faces 60 of the weather-boards are properly painted (and preferably sanded) and the grooves in imitation of rake joints are also properly painted, the wall has the appearance of a well formed brick wall with rake joints.

65 Since the bevel face 12, Fig. 4, is parallel

with the front face 4 of the weather-board, and since the face 10 of the rabbet 6 is parallel with the rear face of the weather-board, it follows that the front faces of all of the weather-boards will lie in the same vertical 70 plane and that the lower thinner edge of each board will fit snugly so as to make a weather-tight joint in the rabbet 10.

When sheathing and building-paper are employed as shown in Fig. 2 and the 75 weather-boards are in place as shown in said figure, there will be formed dead-air spaces 16 which serve to make the building warmer in winter and cooler in summer, since such dead-air spaces form an effective insulation. 80

The invention may be embodied in a variety of mechanical forms, and reference is therefore to be had to the claims hereto appended for a definition of the limits of the invention. 85

What is claimed is:—

1. A weather-board uniformly increasing in cross-section from one edge toward the other and having two longitudinally extending rabbets in its thicker edge portion, each of said rabbets having a bottom at right angles to the front face of the board and one of said rabbets having a face parallel with said front face while the other rabbet has a face inclined therefrom. 95

2. A weather-board uniformly increasing in cross-section from one edge toward the other and having two longitudinally extending rabbets in its thicker edge portion, each of said rabbets having a bottom at right angles to the front face of the board and one of said rabbets having a face parallel with said front face while the other rabbet has an inclined face, the combined bottoms of said rabbets being substantially equal to the thickness of the board at its thinner edge. 100

3. A weather-board uniformly increasing in cross-section from one edge toward the other and having two longitudinally extending rabbets in the front face of its thicker edge portion, each of said rabbets having a bottom at right angles to the front face of the board and a face portion, the face of one rabbet having a surface parallel with the front face of the board while the face of the other rabbet has a surface parallel to the rear face of the board. 110

4. A weather-board which when in position on a vertical wall has a vertical front face and an inclined rear face, said board being provided with two rabbets in the outer face of its upper edge portion, each of said rabbets having a substantially horizontal bottom, the lower rabbet having a face parallel with the front face of the board and the upper rabbet having a face parallel with the said rear face of the board. 120

5. A weather-board which when in posi-

- tion on a vertical wall has a vertical front face and an upwardly and rearwardly inclined rear face, whereby the lower portion of the board is the thinner, and two longitudinally extending rabbets in the front face of the upper edge portion, the combined bottoms of the two rabbets being equal to the thickness of the board at its lower edge. 5
6. A wall comprising a plurality of 10 boards each increasing in cross-section from its lower edge upward, each board being provided in the front face of its upper edge portion with two longitudinally extending rabbets one above the other, the lower edge 15 of each board being received in the upper rabbet of the adjacent board, said boards presenting vertical front faces and being provided with inclined rear faces. 20
7. A wall comprising a plurality of 25 boards, each increasing in cross-section from the lower edge thereof upward, each board being provided in the front face of its upper edge portion with a lower rabbet, and an upper rabbet having a rearwardly inclined wall, the thin edge of each board being received in the upper rabbet of the adjacent board, said boards presenting vertical front faces separated by the lower rabbets, each of said boards having an inclined rear face. 30
8. A wall including in combination a plurality of sheathing boards in direct edge to edge contact and a plurality of weather-boards secured to said sheathing boards, each of said weather-boards increasing in 35 cross-section from the lower edge thereof upward, the upper edge of each weather-board being provided with two longitudinally extending rabbets one above the other, the lower edge of each board being received in the upper rabbet of the adjacent 40 board, said boards having inclined rear surfaces providing with the sheathing a plurality of insulating cells, said weather-boards presenting vertical front faces separated by said lower rabbets and simulating 45 the appearance of a brick wall. 9. A weather-board uniformly increasing in cross-section from one edge toward the other, said weather-board having two longitudinally extending rabbets in its thicker 50 edge portion and a series of transverse grooves extending across one face of the board, each of said grooves having the same width and depth as one of said rabbets. 10. A wall comprising a plurality of 55 boards, each increasing in cross-section from the lower edge thereof upward, each board being provided in its upper edge with two longitudinally extending rabbets one above the other and each board having a series of 60 transverse grooves extending across the front face thereof, the lower edge of each board being received in the upper rabbet of the adjacent board, said boards presenting vertical front faces all in the same plane 65 and separated by the lower rabbets and said grooves.
- In testimony whereof I have signed this specification.
- WILLIAM E. AYCOCK.
